VENTILATING SHUTTER ON VENETIAN BLINDS

Nick Mishlenick, Brooklyn, N. Y.

Application March 22, 1939, Serial No. 263,390

10 Claims. (Cl. 156—17)

This invention relates to window ventilating shutters and more particularly to the type commonly referred to as Venetian blinds.

The principal object of the invention is to provide a Venetian blind structure adapted for installation either exteriorly or interiorly of a window structure and including a plurality of slats operatively connected together at their ends by a lazy-tongs or toggle linkage operatively mounted within a frame including guide tracks to be affixed to each side of the window structure.

A further object of the invention is to provide a locking mechanism to be housed within a casing interconnecting the guide tracks at their lower ends and forming the bottom of the frame and arranged to lock the Venetian blinds in their lowered position, the Venetian blinds further including a latch mechanism for locking the slats thereof in any desired adjusted position as well as for locking the Venetian blind in its uppermost raised position.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings wherein:

Fig. 1 is a view of a window from the inside of the building, with two sets of Venetian blinds, both closed.

Fig. 2 is a view similar to Fig. 1, but the top set of Venetian blinds is shown raised, while the lower set is shown open.

Fig. 3 is a view of a window from the outside of the building with a modified form of single Venetian blind, shown closed, for an entire window.

Fig. 4 is an enlarged partial detail view of the Venetian blind locking mechanism.

Fig. 5 is a sectional view on line 5—5, Fig. 2.

Fig. 6 is an enlarged side elevational view of the Venetian blind raising mechanism in lowered position.

Fig. 7 is an enlarged side elevational view of the raising mechanism in raised position.

Fig. 8 is a detail view of a guide track.

Fig. 9 is a plan view partly in section of the bottom horizontal member of the frame supporting the Venetian blind showing the locking

mechanism used to keep the Venetian blind in its lowered position.

Referring now to the drawings by numerals of reference, and particularly to Figs. 1 and 2, 10 denotes the supporting frame of a Venetian blind which is formed to snugly fit within one-half of a window opening, there being utilized in the window two such frames in superposed relation as clearly shown. In Fig. 3 a single frame 10a is utilized which fits entirely within the window opening and as mounted is shown disposed exteriorly of the window while the half-frames 10 shown in Figs. 1 and 2, are disposed interiorly of the window. Inasmuch as the Venetian blind construction, locking and latching mechanisms as well as operating mechanism are identical regardless of the size of frame supporting structure, a description will only be given as to one frame supporting structure 10 and Venetian blind 11 supported thereby.

The frame 10 comprises vertical guide tracks 12 formed preferably of sheet metal rectangular in cross-section and provided on its inner face 13 with a longitudinal center slot 14. At their lower ends the guide tracks 12 are rigidly connected in any desired manner by a horizontal frame member 15 of wood or metal, a similar frame member 16 being connected to the upper ends of the guide tracks. Obviously the width and length of the window opening will determine the dimensions of the guide tracks 12 and upper and lower horizontal members 15 and 16 which in their interconnected relation define the frame supporting structure 10, which is attached to the window frame 17 by means of screws such as 18, as shown in Fig. 5.

Arranged within each guide track 12 is a toggle linkage 20 of the lazy-tongs or parallelogram type comprising crossed links 21 pivotally connected at their centers as at 22, and at their ends as at 22a see Fig. 6. The length of the lazy-tongs linkage 20 is such that in its extended position it will substantially equal the length of the guide track 12. Fitted between the guide tracks 12 are the slats 25 of the Venetian blind which may be formed of wood, metal or any other suitable material. Each slat 25 is provided at each end with an axial pin 26 carried by a bracket 26a which pin is so connected to each pair of crossed links 21 as to constitute the pivotal connection 22 thereof, the connection being such that the slats 25 and the connected lazy-tongs linkage 20 at each end thereof form a unit handled structure. The lowermost pair of crossed links 21 are pivotally connected by a

pair of links 27 as at 28 to an L-shaped latch plate 29 provided with a horizontal flange 30. The uppermost pair of cross-links 21 are pivotally connected by a similar pairs of links 27a to a bracket 31, which brackets 21 are adapted to fit within the upper open ends of the guide tracks 12 and are further adapted to be secured to the upper horizontal frame member 16 in any desired manner.

10 One of the lower intermediate cross-links 21a is provided with an angular extension 32 and in a like manner one of the upper intermediate links 21b is provided with an angular extension 33, both extensions being on the same side of the lazy-tongs linkage 20. Connecting the extensions 32 and 33 is a tension coil spring 34 which is of a strength such as to contract the lazy-tongs linkage 20 and thereby raise the Venetian blind as shown in Figs. 2 and 7. As the 15 lazy-tongs linkages 20 are completely housed within the guide tracks 12, the raising or lowering of the Venetian blind is guided thereby, the slats 25 being retained in their vertical relationship by the pins 26 slidably guided within the 20 slots 14 of the track guides 12.

25 In order to simultaneously rotate the slats 25 into open or closed position, the same are connected together at their forward edges by a lazy-tongs linkage 35, comprising crossed links 36

30 pivotally connected together at their centers as at 37 and at their ends as at 38. Secured to the forward edge 25a of each slat 25 is a clip 40 having ears 41 between which is rotatably mounted by means of pin 42, a sleeve 43. Each sleeve 43 has fixed thereto a laterally projecting pivot pin 37 which serves as the above mentioned pivotal connection for the cross-links 36. Secured to the lowermost slat 25 is a ring or knob 45 to facilitate the adjustment of the slats 25 into any 40 desired angular position from completely open, see Fig. 2, to completely closed see Figs. 1 and 3. Thus movement of the lowermost slat 25 will be transmitted by the lazy-tongs linkage 35 to impart a like movement to each of the other slats 45 25, said lazy-tongs linkage 35 further co-acting with the lazy-tongs linkages 20 in the raising or lowering of the Venetian blind. If desired, in order to lock the lazy-tongs linkage 35 so as to prevent contraction thereof there is provided a hook latch 46 pivotally connected as at 38a to one of the cross-links 36, the hook latch 46 being adapted to engage an extension formed on the opposite pivot 38b. This locking of the lazy-tongs linkage 35 will insure a rigid interconnection 50 between the slats 25 to effect their simultaneous adjustment, and will further act to prevent unintentional raising of the Venetian blind.

Attached to the upper edge 25a of the lowermost slat 25, see Fig. 4 at one end thereof is a latch 50 carrying a spring pressed bolt 51 provided with a handle 52. Provided on the inner face 13 of the guide-track 12 and adjacent the latch 50 (when the Venetian blind is in its lowered position) is an arcuate row of openings 53 each of which is adapted to receive the bolt 51 for locking the slats 25 in selected angular adjusted position. Adjacent the top of the guide track 12 is an opening 54 which is adapted to co-act with the latch bolt 51 for permanently holding the Venetian blind in its raised position, thus relieving the springs 34.

In order to hold the Venetian blind 11 in its lowered position against the action of the springs 34 tending to raise the same there is provided a locking mechanism carried within the lower hori-

zontal frame member 15. Formed in the frame member 15 is a central recessed opening 60 with which communicates an axial bore 61. At each end of the frame member 15 is an L-shaped plate 62 which is seated in a recess 63 provided therefor so that said plate will be below the surface of the frame member 15. Within each bore 61 is positioned a rod 64 the inner ends of which extend into the opening 60 while the outer ends thereof project outwardly through the vertical plate portion 65 of the L-plate 62. Secured to the outer end of each rod 64 is a latch 66 adapted to project inwardly into the guide track 12 through the slot 14 thereof, said latch 66 being formed with a collar 67 adapted to engage the inside surface 13 of the guide track 12 so as to limit inward movement of the latch 66 under the action of the coil spring 68 surrounding the rod 64 and seated on the plate portion 65 and collar 67. Controlling the latches 66 are a pair of operating levers 69 having a scissor-like action extending within the opening 60 and pivotally connected therein and to said frame member 15 by the pivot 70, the inner ends of said operating levers 69 being connected by a pin and slot connection to the adjacent inner ends of the rods 64.

Thus, with the Venetian blind 11 operatively placed within the supporting frame 10, the lazy-tongs linkages 20 being housed within the guide tracks 12 in the manner as above set forth, the Venetian blind is held in its lowered position against the action of the springs 34 by the engagement of the latches 66 with the horizontal flanges 30 of the latch plates 29, as clearly shown in Fig. 9. To raise the Venetian blind all that is necessary is to draw the operating levers 69 together whereby the latches 66 are disengaged from the latch-plates 29, the blind being then automatically raised by the action of the coil springs 34 in the manner readily apparent.

It is thus seen that the Venetian blind as above described is easily operated and efficient and satisfactory in use. The slats 25 may readily be adjusted and locked in any desired angular position to effect any desired amount of opening thus regulating both the amount of light and ventilation desired. Further by virtue of the locking and guiding mechanism, the Venetian blind provides a construction that will function to prevent entry through the window by a thief or prowler as well as a safety device in preventing the accidental falling out of windows.

Having thus described the invention, what is claimed is:

1. A window shutter comprising a supporting frame adapted to snugly fit within a window opening, a plurality of slats horizontally arranged in superposed spaced relation within said frame, linkage means concealed within the vertical sides of said frame, pivot means connecting each of said slats with said linkage means, said linkage means being adapted to raise or lower said slats, and means carried by said frame for locking said linkage in its lowered position whereby to retain said slats in their lowered position.

2. In the window shutter as set forth in claim 1, wherein said linkage means is vertically contractible and extensible, and spring means connecting spaced portions of said linkage means acting to contract the same upon release of the locking means to thereby raise said slats.

3. In the window shutter as set forth in claim 1, wherein said slats are interconnected at their adjacent edges by a like contractible and exten-

sible linkage for simultaneously turning said slats from an open to a closed position and vice versa, and means carried by said last mentioned linkage for locking the same against movement.

5 4. In the window shutter as set forth in claim 1, wherein said slats are pivotally interconnected at their forward adjacent edges by a like contractible and extensible linkage for simultaneously turning said slats into selected angular positions, releasable hook means carried by said last mentioned linkage for locking the same against movement, and latch means carried by the lowermost slat arranged to coact with a portion of the supporting frame adjacent thereto 10 for retaining said slates in their selected adjusted angular position.

5. A window shutter comprising a supporting rectangular frame having vertical hollow side members connected at their ends by upper and 20 lower horizontal members each of said side members being medially slotted on their inner opposed sides to define a guide track, a lazy-tongs linkage comprising a plurality of interconnected cross-links positioned within each guide track 25 and connected at its upper end to the upper end of said frame, a latch-plate connected to the lower end of each linkage, a plurality of horizontal superposed slats arranged within said frame each 30 stat having at its ends axially extending pins projecting through the slot in said guide track and constituting the pivotal connections of the cross-links constituting said lazy-tongs linkage, whereby contraction or extension of said linkage will impart a corresponding raising or lowering of 35 said slats, and releasable latch means carried by the lower horizontal member arranged to engage each of said latch-plates for locking said slats in their lowered position.

6. In the window shutter as set forth in claim 40 5, wherein said slats are pivotally interconnected at their forward edges by a like lazy-tongs link-

age for simultaneously moving said slats into varying angular positions, and a releasable hook latch provided on said last mentioned linkage to rigidly lock the same against movement.

7. In the window shutter as set forth in claim 5 5, including means interconnecting said slats for effecting simultaneous angular movement thereof, a spring pressed latch bolt mounted adjacent one end of the lowermost slat, an arcuate row of openings formed at the bottom of the inner 10 side of the guide track adjacent said slat end, said openings being adapted to be selectively engaged by said latch bolt for locking said slats in their adjusted angular position.

8. In the window shutter as set forth in claim 15 5, including a tension coil spring connected at its ends to vertically spaced cross-links of each of said lazy-tongs linkages housed within said guide tracks whereby upon release of said latch means said coil springs will act to contract said lazy- 20 tongs linkages to thereby automatically raise said slats.

9. In the window shutter as set forth in claim 5, including releasable locking means carried by the lowermost of said slats for coaction with an 25 upper portion of at least one of said guide tracks whereby to lock said slats in their raised position.

10. In the window shutter as set forth in claim 5, wherein said releasable latch means comprises 30 a pair of rods axially movable within said lower horizontal frame member, each of said rods carrying at their outer ends a latch pin adapted to engage an associated latch-plate, spring means for urging said rods axially outwardly towards 35 said latch plate, and an operating lever arrangement connected to the adjacent inner ends of said rods for moving the same axially inwardly to effect release of said latch means.

NICK MISHLENICK.
